UNITED STATES PATENT OFFICE.

FRANZ BURGER, OF FORT WAYNE, INDIANA, ASSIGNOR OF THREE-FOURTHS
TO HENRY M. WILLIAMS, OF SAME PLACE.

MACHINE FOR CLEANING FABRICS.

SPECIFICATION forming part of Letters Patent No. 614,832, dated November 29, 1898.

Application filed December 10, 1897. Serial No. 661,409. (No model.)

To all whom it may concern:

Be it known that I, FRANZ BURGER, a citizen of the United States, residing at Fort Wayne, in the county of Allen and State of Indiana, have invented certain new and useful Improvements in Machines for Cleaning Fabrics, of which the following is a specification.

This invention relates to certain new and useful improvements in apparatus for cleaning fabrics, it being more particularly adapted for cleaning carpets, rugs, &c., having for its object to provide means whereby carpets may be quickly and effectively cleaned with a minimum expenditure of effort on the part of the operator.

With this object in view the invention consists in the novel construction, combination, and arrangement of the parts hereinafter more particularly described.

In the accompanying drawings, forming a part of this specification, and in which like letters of reference indicate corresponding parts, Figure 1 is a vertical sectional view of the vacuum - generator, parts being in side elevation and broken away. Fig. 2 is a sectional view of the cleaner or extractor. Fig. 3 is a bottom plan view thereof, and Fig. 4 is a detail view of the piston and its valve-operating projection.

Briefly stated, the invention consists of a cleaner or extractor having an open or perforated face adapted to be pressed into contact with the fabric to be cleaned. Connected to this cleaner by means of a flexible tube, which permits the cleaner being moved over an extended surface, is a vacuum-chamber, and coöperating with this chamber is means for generating a vacuum therein. When the cleaner is pressed into contact with the fabric to be cleaned and communication is opened between it and the vacuum-chamber, a suction is created through the open face of the cleaner, and as the air which enters the cleaner must first pass through the fabric any dust or dirt contained therein is drawn into the cleaner with the air, and from thence it passes through the flexible tube and is finally collected in the vacuum-chamber. In order that the cleaner may be used continu-

ously and the necessity of stopping whenever the vacuum in the chamber is so materially decreased as to be insufficient, a second vacuum - chamber is provided, which is likewise adapted to be put into communication with the cleaner. Only one of said chambers is, however, placed into communication with the cleaner at the same time, automatic means being provided which operates in such manner that when one chamber is in communication with the cleaner all communication between the cleaner and the other chamber is cut off, and while the vacuum in one chamber is being utilized a vacuum is being formed in the second chamber ready to be used when that in the first is insufficient to be effective.

Referring more particularly to the drawings, A designates the cleaner or extractor, comprising, as shown, a casing 1, having a chamber 2, from the top of which a discharge-opening leads to a short length of flexible tubing 3, suitably connected to a nipple of the casing. Extending transversely across the bottom of the cleaner is a series of inverted-V-shaped grooves which communicate, through perforations at their contracted portions, with the chamber 2.

In order that the cleaner may be moved over the surface to be cleaned with the least amount of friction, rollers 4 are journaled in its bottom to slightly elevate it above the floor or other surface.

Connected to the sides and ends of the casing are flexible strips 5, which depend below the bottom thereof and prevent air from being drawn into the casing at these points. To the tube 3 is connected a short rigid tubular handle 6, to the end of which in turn is connected a flexible tubular connection 7, leading from the discharge-pipe 8 of a vacuum-generator B. The tubular handle 6 is provided with a hand-valve 6^a, by means of which the suction may be arrested when the cleaner is lifted from the surface being cleaned, thereby preventing the vacuum within the vacuum-chamber being unnecessarily diminished. This generator B when used for dwelling-houses of moderate size may be mounted upon a wheeled truck to facilitate its being moved around from room to room. In large build-

ings, however, it is desirable that it be mounted upon a stationary base, preferably in the basement of the building, and branch supply-pipes provided which extend therefrom to different points in the building, to the ends of which pipes the flexible tube 7 is connected.

As shown, the generator B comprises two vacuum-chambers C C² and a steam-generator D, arranged intermediate the said chambers 10 and communicating therewith through branch steam-supply pipes 9, leading from a common valve-controlled supply-pipe 10, the said branch supply-pipes extending from near the top of the vacuum-chambers to points near 15 the bottoms thereof. Each of the pipes 9 is provided with a seat to which is adapted a valve 12, the stem 12^a of which extends through a discharge-port 13 in the casing of the vacuum-chamber and carries a disk 14, 20 which is adapted to close said port. At its outer end the valve-stem 12^a is connected to a weighted lever 15, pivoted at one end to the casing, and at its free end is adapted to engage a lip of a pivoted vertical projection 25 16, extending from a piston 17 within a cylinder 18. Within this cylinder is a spring 19, the normal tendency of which is to force the piston outward, causing the projection 16 to engage with and lift the end of the lever 15, thereby lifting the valves 12 14 from 30 their seats to open the supply-pipe 9 and discharge-port 13. The projection 16 is provided at its lower end with an extension, which is normally maintained against a solid 35 bearing of the piston by means of a flat spring 20. This spring, however, permits the projection to swing upon its pivot in one direction. The cylinder 18 communicates with the interior of the vacuum-chamber 40 through a port 21, arranged at a point beneath its piston.

Assuming now the parts to be in the position shown in Fig. 1, steam is admitted from the generator D to the bottom of the chamber C through the branch pipe 9. The steam naturally rises within the chamber, forcing the air therein out through the port 13. As it ascends the steam also enters the cylinder 18 through the port 21, and when the pressure 45 is sufficient and all of the air has been expelled from the chamber C the piston and its projection 16 is forced upward, causing the 50 lip of the projection to slip by the end of the weighted lever 15, allowing it to drop, and thereby close the valves 12 14. It will thus be seen that all the air has been expelled from the chamber C and all communication with the external atmosphere and with the steam-generator has been cut off. The external air 55 now begins to cool the casing of the chamber C, condensing the steam therein and causing a vacuum to be slowly produced. The vacuum thus formed pulls down upon the piston 17 and compresses its spring, bringing said 60 parts to the position shown at the right-hand side of Fig. 1. The apparatus is now ready for use, and upon opening communication be-

tween the cleaner and the vacuum-chamber a suction is created through the cleaner and its flexible connection, causing the dust contained in the fabric being operated upon to be drawn within the vacuum-chamber and mingled with the water of condensation in the bottom thereof, from whence it may be withdrawn through a stop-cock 23.

As hereinbefore stated, means are employed which automatically place the chambers C C² alternately into communication with the cleaner, and during the time the vacuum in one of said chambers is being employed a 80 vacuum is being formed in the other. This means comprises, as shown, a valve-casing E, connected at its center to the discharge-pipe 8 and communicating at its opposite ends with the vacuum-chambers C C² through 85 branch discharge-pipes 24. Within this casing E is a slide-valve 25, having two channels 26 27, one of which extends from each end and opens at the side near the opposite end, each of said channels being adapted to register with one of the branch discharge-pipes 24 and the main discharge-pipe 8 when the valve is shifted into proper position. As shown in the drawings, the channel 26 is registering with the discharge-pipe 8 and the 90 branch pipe of the chamber C², the valve having been drawn to the right by the action of the vacuum within the said chamber upon its end, no resistance being offered at the opposite end of the valve. When in this position, 100 the cleaner is in communication with the vacuum-chamber C² and steam is being admitted into the chamber C. As soon, however, as the pressure of steam in the chamber C is sufficient to force the piston 17 outward, thereby 105 releasing the lever 15 and closing the valves 12 14 and a vacuum is formed greater than that in the chamber C², the valve is drawn to the left, placing the chamber C into communication with the cleaner through the port 27 110 and cutting off the communication between the chamber C² and the cleaner. By this time the vacuum in the said chamber C² has become so materially decreased that the spring 115 19 raises the piston 17, causing the lip of the projection 16 to lift the end of the lever 15 and open the valves 12 14 of the said chamber, allowing steam to enter the chamber preparatory to forming a vacuum therein.

In order to insure the proper action of the 120 valve 25, it is provided in its under face with a recess 29, into which extends a short arm 30 of a rock-shaft 31. This shaft extends through the casing and is provided at its outer end with a weighted lever 32. When thus constructed, 125 it will be readily seen that if the valve 25 be moved a little over one-half its stroke the weighted lever will be carried to one side or the other of the vertical and by gravity assist the valve in the completion of its stroke.

Without limiting myself to the exact construction and arrangement of the parts shown and described, since it will be evident that various changes in such construction and ar-

angement may be made without departing from the spirit or scope of my invention,

What I claim is—

1. In a cleaning apparatus, the combination of a cleaner comprising a closed casing having a grooved face said grooves being contracted in cross-section and communicating with the casing at their contracted portions, a vacuum-chamber and a flexible tubular connection intermediate the vacuum-chamber and cleaner, substantially as described.
2. In a cleaning apparatus, the combination with a cleaner comprising a casing having an open or perforated face two vacuum-chambers, a flexible tubular connection intermediate the cleaner and said chambers and automatic means for placing the vacuum-chambers alternately in communication with the cleaner, substantially as described.
3. In a cleaning apparatus, the combination with a cleaner comprising a casing having an open or perforated face two vacuum-chambers, a flexible tubular connection intermediate the cleaner and said chambers and automatic means for placing the vacuum-chambers alternately in communication with the cleaner, and automatic means for creating a vacuum in the said chambers, substantially as described.
4. In a cleaning apparatus, the combination with a cleaner, of a vacuum-chamber having a valve-controlled discharge-port, a flexible connection between the cleaner and vacuum-

chamber, a steam-generator, a valve-controlled connection intermediate the steam-generator and vacuum-chamber and means adapted to be actuated by the pressure within said chamber to automatically close the discharge-valve and the valve intermediate the chamber and generator, substantially as described.

5. In a cleaning apparatus, the combination with a cleaner, of two vacuum-chambers, a flexible connection intermediate the chambers and cleaner, means for automatically placing said chambers alternately in communication with the cleaner, and automatic means for alternately generating a vacuum in the vacuum-chambers, substantially as described.

6. In a cleaning apparatus, the combination of a cleaner having a perforated or open face, a vacuum-chamber having a valve-controlled discharge-port leading therefrom, a connection between said chamber and the cleaner, a steam-generator and a valve-controlled communication intermediate the generator and vacuum-chamber, substantially as described.

In testimony whereof I have signed my name to this specification in the presence of two subscribing witnesses.
